Specification of Letters Patent.

Patented Feb. 6, 1917.

Application filed June 25, 1913. Serial No. 775,624.

To all whom it may concern:

Be it known that I, ELLSWORTH A. HAWTHORNE, a citizen of the United States, and a resident of Bridgeport, county of Fairfield, and State of Connecticut, have invented an Improvement in Lamps, of which the following description, in connection with the accompanying drawings, is a specification, like characters on the drawings representing like parts.

This invention relates to lamps, being more especially though not exclusively concerned with electric lamps intended for use on vehicles and subjected to continual vibration when in use.

My invention will be best understood by reference to the following specification when taken in connection with the accompanying drawings of one specific embodiment thereof, while its scope will be more particularly pointed out in the appended claims.

In the drawings:

Figure 1 is a rear elevation of an electric tail lamp embodying my invention;

Fig. 2 is a sectional view on line 2—2 of Fig. 1 illustrating the manner in which the red "jewel" is removed from and replaced in the lamp casing;

Fig. 3 is a sectional view on line 3—3 of Fig. 1 illustrating the locking device which prevents the bezel from rotating;

Fig. 4 is a sectional view on line 4—4 of Fig. 2 illustrating the device which prevents the lamp bulb from accidentally unscrewing;

Fig. 5 is a sectional view on line 5—5 of Fig. 4; and

Fig. 6 is a bottom plan of a portion of the lamp illustrating the mode of fastening the bottom light transmitting element.

Referring to the drawings and to the embodiment of my invention which I have selected for illustrative purposes, I have there shown an electric tail lamp of the type in which a portion of the light rays serve to illuminate a registration number plate, while the remainder serve to light a red rear light-transmitting element.

The illustrative lamp shown comprises a casing 7 for an appropriate lamp 8 which may be and preferably is an electric incandescent bulb having a usual shell threaded into a socket 10. When lamps of this description are in use on vehicles, the great and continual vibration to which they are subjected is very apt to cause the electric

bulb to unscrew from its socket and drop into the bottom of the lamp casing. To remedy this difficulty, I have herein provided means normally to prevent the bulb from unscrewing from the socket, such means in the present instance comprising a spring arm 11 secured at 12 in any appropriate manner to the lamp casing as by providing the latter with a lug in which one end of the arm is soldered.

Intermediate its ends, the arm 11 is preferably bent to form a depression 13 fitted into the thread of the shell 9. The arm is caused to bear with a firm pressure against the shell by having its free end normally held in fixed position as shown in the drawings. For this purpose, I preferably provide the casing 7 with a hooked lug 14 punched out of the metal forming the casing and adapted to lock the arm in a manner best shown in Fig. 5. By this means, the lamp bulb is normally securely held and prevented from unscrewing yet may be removed from its place by simply depressing the terminal portion of the arm 11 downwardly and unhooking it from the lug 14 thus freeing the bulb and allowing the latter to be unscrewed.

The lamp casing may have any suitable provision for causing a portion of the rays of light to be shed upon a registration number plate placed below the lamp, but herein the casing is provided in its bottom with an opening 15 covered by a suitable light transmitting element 16 which may be and preferably is in form of a sheet of celluloid which is most suitable for the purpose since the shocks and vibrations to which it is subjected will not cause it to break. This light transmitting element at its marginal portion overlies the bottom surface of the lamp casing in a manner most clearly shown in Fig. 6 and is securely held in this position by means of a plurality of lugs overlying the bottom surface of the marginal portion of the light transmitting element. Herein I have provided the lamp casing with two pairs of lugs 17 overlying the longitudinal edges of the light transmitting element and a pair of lugs 18 overlying the ends thereof, all of which lugs are preferably formed by slitting or punching the metal of the casing to form tongues and then depressing such tongues to a sufficient extent to form a space for the insertion of the light transmitting 110

element between the upper faces of the lugs and the bottom face of the casing. By this means, the light transmitting element is securely held in its place without the use of 5 any loose parts which would tend to become detached when subjected to shocks and vibrations.

The lamp casing is provided in its rear wall with an aperture 19 in which is 10 mounted a suitable bezel 20 holding an appropriate light transmitting element, herein what is commonly called a red "jewel" 21. The rear face of this bezel overlies the margin of the casing about the aperture 19 while 15 the bezel is herein provided with a flange 22 extending through the aperture to the interior of the casing. This flange may be and preferably is provided with a pair of lugs 23 herein formed by slitting or punching 20 the metal which forms the flange to form tongues which are then bent in an outward direction so as to be capable of engaging the inner face of the casing thereby to interlock with the latter and normally prevent 25 the bezel from being withdrawn axially.

The casing 7 is herein provided with a notch 24 through which one of the lugs 23 may be introduced and then turned to a position 30 where it will be out of register with the notch. The manner of inserting the bezel is most clearly shown in Fig. 2 from an examination of which it appears that one of the lugs 23 is first inserted while the bezel is 35 in a somewhat angular position and the other lug is then introduced through the notch 24 into the interior of the casing after which the bezel is rotated until the lugs interlock with the margin of the casing 40 about the aperture, thus preventing the bezel from being withdrawn axially.

Were it not for the provision of some means to prevent the bezel from rotating after being put in place as described, the 45 vibration to which the lamp is subjected would tend to rotate the bezel until one lug or the other comes into register with the notch in the casing and the bezel with its jewel would drop out of place. To prevent 50 such an accident, I provide suitable means normally to hold the bezel against rotation. Such means may be and preferably is in the form of a yielding arm 25 secured in any appropriate manner to the casing as by 55 means of a rivet 26 and having its free end interlocking with the bezel in any appropriate manner. Herein the latter is provided with two notches 27 formed in the flange 22 by a removal therefrom of the metal which 60 is punched out to form the lugs 23. The free end of the spring arm 25 is made slightly narrower than the width of the notches 27 and when the bezel is rotated from the position shown in Fig. 2 to the position shown

in Fig. 1 the free end of the arm will snap 65 into place in one of the notches 27 thereby effectually locking the bezel against rotation.

The casing is herein provided with an aperture 28 through which the locking member 25 is accessible for the purpose of releasing the same from its interlocking engagement with the bezel. To facilitate the unlocking of the bezel, the member 25 is herein provided with a projection 29 extending 70 through the aperture 28 to a position where it may be readily engaged by one's finger and pressed inwardly thereby withdrawing the locking member out of the notch 27. When this has been done, the bezel 80 may be rotated until one of the lugs 23 registers with the notch 24 after which the bezel is removed by withdrawing the lug through the notch in the manner shown in Fig. 2.

As a means for preventing the lug 23 from 85 being rotated beyond the notch 24 in one direction, I may provide a lug 30 extending inwardly across the path of the lug 23 as best shown in Fig. 2. While this lug may be formed in any other appropriate manner, I prefer to form the same of the metal which is punched out to form the notch 24 as will be clearly apparent upon an inspection 90 of Figs. 1 and 2. Owing to the presence of this lug, when the bezel is rotated from 95 the position shown in Fig. 1 and toward the position shown in Fig. 2, the lug 23 will bring up against the lug 30 and prevent the bezel from being rotated further, thus apprising the operator that the bezel is now in 100 position with one of the lugs registering with the notch 24.

While I have herein shown and described one form of my invention for illustrative purposes and have described and discussed 105 in detail the construction and arrangement incidental to one specific application thereof, it is to be understood that the invention is limited neither to the mere details or relative arrangement of parts nor to its specific application herein shown, but that extensive deviations from the illustrated form or embodiment of the invention may be made without departing from the principles thereof.

Having thus described one embodiment of my invention, what I claim and desire by Letters Patent to secure is:

1. In a lamp, the combination of a casing 110 provided with an aperture, a bezel mounted in said aperture and having means normally to prevent said bezel from being withdrawn axially, said casing having provision to permit said bezel to be rotated to a position to permit the same to be detached 115 from said casing, and a yieldingly mounted finger normally interlocking with said bezel to hold the same against rotation, said cas-

ing being provided with an aperture, through which said finger is accessible from the exterior of said casing.

2. In a lamp, the combination of a casing provided with an aperture, a bezel mounted in said aperture and having a plurality of lugs engaging an inner face of said casing normally to prevent said bezel from being withdrawn axially, said casing having provision to permit said bezel to be rotated to a certain position and then withdrawn axially, said bezel being provided with a notch, and a locking member within said casing normally located in said notch to lock said bezel against rotation, said casing being provided with an aperture through which said locking member is accessible.
3. In a lamp, the combination of a casing provided with an aperture, a bezel mounted in said aperture and having a plurality of lugs engaging an inner face of said casing normally to prevent said bezel from being withdrawn axially, said casing having provision to permit said bezel to be rotated to a certain position and then withdrawn ax-
- ially, said bezel being provided with a notch, said casing being provided with an opening, and a locking member within said casing normally engaging said notch to lock said bezel against rotation, said locking member being provided with a projection extending through said opening.
4. In a lamp, the combination of a casing provided with an aperture, a bezel mounted in said aperture and having a plurality of lugs engaging an inner face of said casing normally to prevent said bezel from being withdrawn axially, said casing being provided with a notch through which one of said lugs may be introduced and then turned out of register with said notch, means to limit the rotation of said bezel when the lug is in register with said notch, and means normally to lock said bezel against rotation.

In testimony whereof, I have signed my name to this specification, in the presence of two subscribing witnesses.

ELLSWORTH A. HAWTHORNE.
